UNITED STATES PATENT OFFICE

2,520,405

PORTABLE PIT

George O. Hoffstetter, Jerseyville, Ill.

Application July 29, 1946, Serial No. 686,921

2 Claims. (Cl. 189—34)

1

This invention relates to a removable conveyor pit.

An object of this invention is to provide a pit for insertion beneath a railroad track so that the material may be dumped from a car into the pit and then conveyed by means of a portable conveyor to a truck or the like. In this manner the car can be unloaded at any selected point on a siding, thus eliminating the necessity of shunting the car to an overhead track associated with a bin or the like.

Another object of this invention is to provide a pit for a portable conveyor which can be shifted from point to point, it being only necessary to dig beneath the tracks between a pair of ties and then insert the pit so that the car can be dumped between the tracks and the material promptly removed.

A further object of this invention is to provide a portable pit of this kind which is of simple and strong construction and can be applied and removed in a very short time.

With the above and other objects in view, my invention consists in the arrangement, combination and details of construction disclosed in the drawings and specification, and then more particularly pointed out in the appended claims.

In the drawings,

Figure 1 is a detail top plan of a portable conveyor pit constructed according to an embodiment of this invention.

Figure 2 is a longitudinal section of the device, Figure 3 is a sectional view taken on the line 3—3 of Figure 2.

Referring to the drawing, the numerals 10 and 11 designate a pair of railroad rails which are mounted on cross ties 12, 13. In order to provide a means whereby a railroad car may be dumped at a point where there is no permanent pit or bin, I have provided a portable conveyor pit of trough-like construction, generally designated as 14. The pit 14 includes vertically disposed side walls 15 having a bottom 16 fixed thereto.

The side walls 15 converge toward one end or back of the pit and at the small end an upwardly and outwardly extending end wall 17 is secured to the side walls 15. The side walls 15 also have extending inwardly therefrom a pair of reinforcing flanges 18, 19, which are shorter in length than the upper edges of the side walls and these side walls are also reinforced for the remainder of their lengths by outwardly extending flanges 20, 21.

The pit 14 is also reinforced or strengthened by means of substantially U-shaped angle bars having vertical sides 22 fixed to the outer sides of the side walls 15, and also having bights 23 extending across the open upper side of the pit 14. The large open end 24 of the pit is adapted to have extending thereinto, the lower receiving end of an endless conveyor 25.

In the use of this pit, the space between the two ties 12, 13, which have been shifted sideways

2

to form a wide spacing, is hollowed out so that the pit 14 can be inserted between the two ties 12, 13, and below the rails 10, 11. The open end 24 of the pit 14 is disposed on the desired side of the track so that the conveyor 25 may be extended into the open end 24 for removing the material discharged into the pit.

With the construction as hereinbefore described, the railroad car can be dumped on any siding and the material promptly removed from beneath the car. This pit will, with a portable conveyor, provide a means for reducing mileage in trucking the material received from the railroad car and will facilitate the unloading of the car as the material can be removed by the conveyor as soon as the pit 14 becomes substantially filled. After the car has been emptied, the pit may be removed and the hollowed space re-filled with the roadbed material.

I do not mean to confine myself to the exact details of construction herein disclosed, but claim all variations falling within the purview of the appended claims.

What I claim is:

1. A conveyor pit for insertion beneath a railroad track, comprising a trough-like structure formed with a plane bottom, vertical side walls secured to said bottom and converging toward one end, a back wall extended across the convergent ends of said side walls to form a closed end, said back wall being inclined upwardly and outwardly from said bottom, said side walls being formed with top edges converging toward said bottom to form an open end disposed from said back wall of lesser height relative to said closed end, said top edges being formed with inwardly extending right angular flanges having terminating ends disposed from said closed end, a substantially U-shaped brace disposed from said closed end and positioned exteriorly of said side walls having a top portion connecting said top edges adjacent said terminating flange ends, and outwardly extending right angular flanges carried by said edges and extending from said U-shaped brace to said open end.

2. A conveyor pit as claimed in claim 1 having an intermediate U-shaped brace engaging the side walls forwardly of the back wall and rearwardly of the first mentioned U-shaped brace.

GEORGE O. HOFFSTETTER.
